UNITED STATES PATENT OFFICE.

HENRY LELAND LOWE, OF PITTSBURGH, PENNSYLVANIA.

GAS-ANALYZING APPARATUS.

1,186,014.

Specification of Letters Patent.

Patented June 6, 1916.

Application filed February 27, 1911. Serial No. 611,219.

To all whom it may concern:

Be it known that I, HENRY LELAND LOWE, a resident of Pittsburgh, in the county of Allegheny and State of Pennsylvania, have 5 invented a new and useful Improvement in Gas-Analyzing Apparatus; and I do hereby declare the following to be a full, clear, and exact description thereof.

My invention relates to gas analyzing apparatus, and has special reference to an apparatus for analyzing gases used in mills, plants, and other places, such as waste and other gases for operating gas engines, etc.

The object of my invention is to provide 15 a simple and efficient apparatus for use in connection with the application of what is known as "Dalton's law" to the volumetric analysis of gases.

To these ends my invention consists, generally stated, in the novel arrangement, construction and combination of parts of the apparatus, as hereinafter more specifically set forth and described and particularly pointed out in the claims.

25 To enable others skilled in the art to which my invention appertains to construct and use my improved apparatus for analyzing gas, I will describe the same more fully, referring to the accompanying drawings, in 20 which—

Figure 1 is a front elevation of my improved apparatus for analyzing gases. Fig. 2 is a side elevation of the same. Fig. 3 is a front elevation, partly broken away, of 25 a modification of the indicating and recording device. Fig. 4 is a side elevation of the same. Fig. 5 is an enlarged sectional view of the gas entrance union and its connections. Figs. 6, 7 and 8 are detail views of 40 the distributing cock employed. Fig. 9 is a sectional view of one of the valves employed. Figs. 10, 11, and 12 are enlarged detail views of the recording device and its immediate operating mechanism.

45 Like symbols of reference herein indicate like parts in each of the figures of the drawings.

In the application of Dalton's law to the volumetric analysis of gases, such law states 50 that the product of the pressure and volume of a mixture of gases is equal to the sum of the products of the pressure and volumes of the constituents, measured at the same temperatures. Therefore, the ratios of the pressures of a number of samples of gases, measured at equal volumes, is equal to the ratios

of the volumes of the samples measured at equal pressures. If the pressures are measured at unequal volumes, then the ratios of the products of each pressure and a constant, 60 is equal to the ratio of the volumes measured at equal pressures.

To apply such theory to an apparatus for the analysis of the gases it is necessary to mechanically draw into two vessels simultaneously a sample of the gas to be analyzed and bring the contents of one vessel into contact with a solution which will absorb the constituent or constituents desired. Then 65 separate the remaining gas from the solution and return the gas to the original or another vessel, and by mechanical means indicate or record, or both, the ratio of the difference in pressures between the treated and untreated gas to the pressure of the untreated 70 gas which will be equal to or proportional to the volumetric analysis, so that if a dial or chart is used on which the indication or record is made be divided properly, the analysis 75 may be read directly in per cent.

The gas analyzing apparatus as hereinafter described is enabled to give approximately correct indications by reason of the slowness in the change of atmospheric pressure, and the results will at all times be almost absolutely correct. In such apparatus there horizontally disposed cylinders 1, 2 and 3 are shown with axes parallel, which are provided with a piston (not shown) in each of the same and having a hollow piston rod 4 connected to each of the same and extending through each end of said cylinders so as to be connected to a yoke 13 at both ends of said rods and between the same in order that the middle of power 80 cylinder 2 can drive the other two cylinders 1 and 3. The power cylinder 2 is preferably driven by water pressure applied thereto by the water from the supply pipe 5' entering the union 5 where it passes through a very small hole 5'' in a diaphragm 5^a therein and thence is carried to the distributing 85 cock 6 by the pipe 7. This cock 6 supplies the water to alternate ends of the cylinder 2 by the pipes 8 and 9 and with the parts 100 as shown in Fig. 1 the pistons are in the position nearing the end of the stroke on the right hand end of the cylinders 1, 2 and 3. The water enters the cylinder 2 on the left by the pipe 8 and the cock lever 10 connected to the cock 6 is drawn by the rod 11 connected to said lever and post 12 on the 105 110

yoke 13 to the right, which will put the cock spring 14 connected between said cock and lever under sufficient tension to move such cock through an angle slightly exceeding 90 degrees when said cock is released, so that the water in the right hand end of the said cylinder passes through the pipe 9 to the discharge pipe 15 by means of the said cock, and such pipe discharges such water through the cooler 16 into the drain 17 leading from said cooler.

The cock 6 carries the two pins 18 and 19, which alternately engage with the pin 20 on the pivoted lever 21, and the engagement of the pins 18 and 20 prevents a rotation of the said cock in a clockwise direction. When the pistons in the cylinders 1, 2 and 3 reach the end of their stroke to the right and further movement of the same is prevented by the heads on said cylinders, the water pressure in the system to the right of the diaphragm 5^a in the union 5 rises to the full pressure of the water in the pipe 5' to the left of such diaphragm and forces a small plunger 6" in the body of the cock 6 out against the lever 21, which raises said lever against the action of the spring 22 engaging with the same and releases the pin 18, so that such cock rotates until stopped by the pin 18 striking against the stop 23 on such cock casing. After the lever 21 has returned to its original position the pin 19 will engage with the pin 20 and thereby prevent a rotation of said cock in a counter clockwise direction. The passage 6^a in the cock 6 will now connect the supply pipe 7 on the right hand end of the cylinder 2 through the pipe 9, while the pipe 8 is connected with the discharge pipe 15 through the other passages 6^b in said cock, so that the pistons in the cylinders will move toward the left end of such cylinders until the end of the stroke of the same is reached and then the operation of said pistons and parts 45 is repeated in the reverse direction.

The cylinders 1 and 3 are used for the purpose of containing gas, and when their pistons move toward the right it will cause a reduction of pressure of the contents at the left hand end of the cylinder 1, and this reduction in pressure during the movement of the pistons will continue until such pressure has dropped sufficiently to establish a flow of the gas to be analyzed through the pipe 25 within the cooler 16, and connected to the union 24 on the top end thereof. The pipe 25 extends into the water in the container 26, and as the gas passes through the said pipe into the said water it bubbles up through the same and becomes saturated with water vapor at the existing temperature, after which it passes through the pipe 27 connected to said container above the water therein and through the check valve 29 in said pipe into the cylinder 1.

The check valve 30 in the pipe 27 does not open as the piston in the cylinder 1 moves to the right, as the pressure with said cylinder keeps said valve closed, and the arrows on the check valves show the directions in which the fluids may pass through them. In the meantime the contents of the said cylinder 1 on the right hand end, such as having been drawn into the cylinder in the previous stroke to the left in a manner similar to that just described, is compressed until its pressure rises sufficiently to establish a flow of the gas through the pipe 31, check valve 32, and pipe 34 to the container 35, which contains the solution which will absorb the constituent or constituents of the gas desired, where it bubbles through said solution with certain portions being absorbed thereby and the remainder delivered to the pipe 36 leading from said container. To prevent a possible flow of the gas through the pipe 37 and check valve 38 into the container, the check valve 38, as well as the check valve 32 in the pipe 31 is spring operated in any suitable manner to hold the valve to its seat. The gas after treatment in the container 35 passes through the pipe 36, check valve 40 and pipe 41 to the left hand end of the cylinder 3 and the gas in the right hand end of said cylinder is pressed out through the check valve 32 into the atmosphere, or can be delivered to a second analyzing unit to analyze another constituent of the gas.

The contents of the cylinder 1 is in communication with the aneroid 44 by means of the pipe 43. The contents of the cylinder 3 is similarly in communication with the aneroid 46 by the pipe 45, this aneroid being subjected to the same external atmospheric pressure. These aneroids 44 and 46 are connected together by means of the rod 47 and made integrally solid with the block 48. If this rod 47 and block 48 were absent the aneroid 44 would be deflected to a degree proportional to the difference in pressure between the contents of the cylinder 3 and the atmosphere. Similarly the aneroid 46 would be deflected to a degree proportional to the difference in pressure between the contents of the cylinder 3 and the atmosphere. Connecting them rigidly, however by the rod 47 and the block 48 produces a combined deflection or movement of the rod 47 and block 48 which is proportional to the difference in pressure between the contents of the cylinder 1 and the cylinder 3. This motion of the block 48 is communicated to the lever 52 which is pivoted on the pin 52^a, which in turn is rigidly secured to the frame 50 of the instrument. The motion of this lever 52 is further communicated to the bell crank 53 by means of the lever 57, and the pin 55 secured to the reach rod 58. The bell crank 53 transmits the motion to bell crank 54 180

which moves over the surface of the paper not touching it, the ink thread 63 passing between the pointer on the bell crank 54 and the paper 59'.

5 The illustration of the lever 52 in Fig. 10 as being in front of the bell crank 53 is made simply for convenience of illustration.

To supply an extra torque to the aneroids to restrict the motion of the pointer 54 to 10 within the bounds of the paper for the difference in pressure in the cylinders 1 and 3 to be measured, the flat spring 49 is provided. This spring 49 is rigidly secured to the block 48 and is clamped to the frame 50 15 by means of the screw shown in clamp block 52'. The clamp 51 may be so adjusted as to alter the length of the flat spring 49 and consequently change the external torque on the aneroids so that for a given pressure 20 difference any scale deflection desired may be obtained. This torque, it will be seen from the character of the spring, is proportional to the deflection of the block 48. It is desirable to record this difference in pressure 25 in the aneroids 44 and 46 only when the analysis has been completed, that is when the pistons in the cylinders 1 and 3 have reached the ends of their strokes. When the end of the stroke is reached, therefore, the mechanism 30 is so arranged that the rod 65 is raised and depresses the bell crank 64 against the end of the bell crank 54, pressing the end of the latter against the inked thread 63 and forcing the inked thread against the paper 35 59' with sufficient pressure to make a mark thereon. This mark on the paper referred to the zero line on the paper, that is the position which the pointer on the bell crank 54 takes when the pressure in the aneroid 44 40 is equal to the pressure in the aneroid 46, is a measure of the difference in pressures in the aneroids 44 and 46 and consequently the difference in pressures in the cylinders 1 and 3.

45 If the absolute pressure of the gas in the cylinder 1 is constant, this record on the paper 59' measured above the zero line on the paper is a measure of the analysis of the gas by Dalton's law. In practice, however, 50 the gas would be delivered to the cylinder 1 at a constant pressure above or below atmospheric pressure instead of at an absolute constant pressure. The record on the paper 59', therefore, represents a true analysis of the 55 gas as long as the atmospheric pressure is constant. Should this vary, the distances on the paper 59' would have to be measured to a new scale or the ratio of the lever arms in the instrument would have to be altered 60 to give a correct analysis at the existing scale of the paper. For this reason aneroid 56 is provided, which is deflected by changes in atmospheric pressure, moving the pin 55, whereby the action of the lever 52 is communicated to the bell crank 53 up and down

in the slot provided in the end of the lever and the end of the bell crank. It will be seen from the drawing that an increase in atmospheric pressure will collapse the aneroid 56, moving the rod 58 downward by 70 means of the lever 57, thereby moving the pin 55 nearer the pin 52', shortening the longer arm of the lever 55 and lengthening the shorter arm of the bell crank 53, thereby reducing the deflection of the end of the 75 bell crank 54 for a given motion of the block 48 which connects aneroids 44 and 46.

Fluctuations in atmospheric pressures are not great, and, therefore, this correction applied through the aneroid 56, lever 57, arm 80 58 and pin 55 may not be made precisely, due to the fact that errors therein will, to a very slight degree, be reflected in the result desired, viz: the analysis of the gas.

A roll of paper as at 59 is adapted to be 85 fed between the surfaces of the cylinders 60 and 61 by any suitable clock 62 connected to the shaft 60' of said cylinder 60, while in front of the paper and parallel with the axis of the said cylinder passes an inked thread 63, which also passes around suitable rollers 63' supported on the frame 50, and above said thread swings the pointed end 54' of the bell crank 54. A broad bell crank 64 is adapted to press the end 54' of the crank 54 against the thread 63, which in turn is pressed against the paper 59', thereby making a mark and recording the position of such bell crank end 54' at the particular movement, after which the crank 64 is immediately released and the crank 54 swings freely again. The crank 64 is actuated by the reach rod 65, one end of which is connected to the short arm of said crank, as at 65', and the other end of which is connected to the arm 66 secured to the cock 6, so that the record of the crank 54 on the paper 59' from the roll 59 through the medium of said crank 64 is only made when the pistons in the cylinders are at the end 90 of their strokes, and if the said paper is ruled to the proper scale the record thereon, as so given, will give the analysis of the gas.

In case it is desired to analyze for another constituent or group of constituents 115 the discharge gas from the above described apparatus may be piped to the intake of a similar one and the operation repeated with another absorbent.

In Figs. 3 and 4 is shown an apparatus 120 for indicating, as well as recording the analysis of the gas, in which case the rod 65 of the apparatus is connected to the cock 67 by the arm 67', and the pipe 43 transmits the pressure from the cylinder 1 to said cock, 125 while the pipe 45 transmits the pressure in the cylinder 3 also to said cock, so that each time the cock 6 changes position the reach rod 65 will open said cock 67 momentarily and the pressure in the pipe 43 is trans- 130

mitted to aneroid box 68 by the pipe 69 while the pressure in the pipe 45 is transmitted to aneroid box 70 by the pipe 71. These aneroid boxes 68 and 70 are connected by the rod 72 carrying the pin 73, and the motion of said pin depends upon the difference in pressure in the two boxes and can be controlled by a flat spring, as before described, for the recorder, if desired. The lever 74 formed of suitable materials and fitting around the pin 73, transmits the motion to the bell crank 75 to which it is pivoted at 74' and is also pivoted to the short arm 75', and its longer arm 75'' carries the pen 76 at its end so such pen makes a trace on the circular paper 77 secured to a clock driven dial 78 and turning around the axis 79. The lever 74 has its fulcrum in one end of the lever 80, which is actuated by the aneroid barometer 81 to which said lever is pivoted at 80', and this barometer makes a correction to the deflection of the bell crank 75, so that the record on the dial 78, when read to the proper scale, as divided on the paper 77, will give the analysis of the gas, while correction for temperature in said barometer is accomplished by the materials of which lever 74 is constructed.

It will be evident that the motor formed by the cylinder 2 can be replaced by any other kind of an engine or motor, or other means may be substituted in order to operate the gas cylinders 1 and 3, and while the apparatus shown and described is automatic in its operation, it will be obvious that other forms or devices can be constructed and used for both laboratory and plant work, and which may either be automatic or non-automatic in their operations, so that various modifications and changes in the apparatus employed in my improved analyzing of gases may be resorted to, without departing from the spirit of the invention or sacrificing any of its advantages.

It will thus be seen that my invention in connection with the improved apparatus for analyzing gases will be well adapted in use for the purpose for which it is intended and the analysis of a constituent or constituents in the gas can be made sufficiently accurate, as desired.

What I claim as my invention and desire to secure by Letters Patent is—

1. An apparatus for analyzing gases, comprising means for measuring the ratio of the pressure of the gas after treating with an absorbent to the pressure of the gas before such treatment.

2. An apparatus for analyzing gases, comprising means for measuring the ratio of the pressure of the gas after treating with an absorbent to the pressure of the gas before such treatment and recording the same.

3. An apparatus for analyzing gases, comprising means for measuring the ratio of the

difference of the pressure of the gas before and after treatment with an absorbent to the pressure of the gas before such treatment.

4. An apparatus for analyzing gases, comprising a container for holding a sample of the gas desired to be analyzed, another container, and means for removing such gas from said first named container and passing the same through an absorbent to remove a desired constituent and into said last named container, and means for measuring the ratio of the difference of the pressure of said gas before and after treatment with said absorbent to the pressure of the gas before such treatment. 80

5. An apparatus for analyzing gases, comprising a container for holding a sample of the gas desired to be analyzed, another container, and means for removing such gas from said first named container and passing the same through an absorbent to remove a desired constituent and into said last named container, and means for measuring the ratio of the difference of the pressure of said gas after treatment with said absorbent to the pressure of the gas before such treatment. 90

6. An apparatus for analyzing gases, comprising a container for holding a sample of the gas desired to be analyzed, another container, and automatic means for removing such gas from said first named container and passing the same through an absorbent to remove a desired constituent and into said last named container, and means for measuring the ratio of the difference of the pressure of said gas before and after treatment with said absorbent to the pressure of the gas before such treatment. 95

7. An apparatus for analyzing gases, comprising a container for holding a sample of the gas desired to be analyzed, another container, and automatic means for removing such gas from said first named container and passing the same through an absorbent to remove a desired constituent and into said last named container, and means for measuring the ratio of the difference of the pressure of said gas after treatment with said absorbent to the pressure of the gas before such treatment. 100

8. An apparatus for analyzing gases, comprising a container for holding a sample of the gas desired to be analyzed, another container, automatic means for removing such gas from said first named container and passing the same through an absorbent to remove a desired constituent and into said last named container, and means for measuring the ratio of the difference of the pressure of said gas before and after treatment with said absorbent to the pressure of the gas before such treatment, and means for indicating the ratio of such pressures. 110

9. An apparatus for automatically analyzing gases, comprising a container for hold- 120

means within said containers for passing the sample of the gas out of the same and for drawing in another, and means connected to said pistons for reciprocating the same.

17. An apparatus for automatically analyzing gases, comprising a container for holding a sample of the gas desired to be analyzed, a container for holding a sample of the gas after treatment, pistons in said containers for passing the gas to be treated from said first named container through an absorbent to remove a desired constituent from said gas and to pass the remaining part of such gas into said last named container, and means for measuring the ratio of the difference of the pressures of said gas before and after treatment to the pressure of a succeeding untreated sample in the first named container, reciprocating means within said containers for passing the sample of the gas out of the same and for drawing in another, means connected to said pistons for reciprocating the same, rods connected to said pistons and extending through said containers, and means connected to said rods for reciprocating said pistons.

18. An apparatus for automatically ana-

lyzing gases, comprising a container for holding a sample of the gas desired to be analyzed, a container for holding a sample of the gas after treatment, pistons in said containers for passing the gas to be treated from said first named container through an absorbent to remove a desired constituent from said gas and to pass the remaining part of such gas into said last named container, and means for measuring the ratio of the pressure of said gas after treatment to the pressure of a succeeding untreated sample in the first named container, reciprocating means within said containers for passing the sample of the gas out of the same and for drawing in another, means connected to said pistons for reciprocating the same, rods connected to said pistons and extending through said containers, and means connected to said rods for reciprocating said pistons.

In testimony whereof, I, the said HENRY LELAND LOWE, have hereunto set my hand. 50
